JOHN H. CHAPMAN, OF UTICA, NEW YORK.

Letters Patent No. 63,212, dated March 26, 1867.

IMPROVED MODE OF ELEVATING HAY FORKS.

The Schedule referred to in these Letters Patent and making part of the same.

TO ALL WHOM IT MAY CONCERN:

Be it known that I, JOHN H. CHAPMAN, of Utica, New York, have invented a new and useful Improvement in the Mode of Elevating Hay Forks and the like.

The nature of my invention consists in the use of a turning post and casting-off pulley in connection with the ropes and pulleys in use in such cases. Where the usual rope and pulleys are used, the draught is in a straight line from the lower or ground pulley, and as barn-yards are sometimes small, or there may be something in the way, it becomes inconvenient at times to raise the load to the desired point. And then, again, when the load has been raised it is necessary to back up the horse to allow the fork to descend. To obviate these objections I set a stout post in the yard; at, say, about half the distance from the lower pulley the horse would have to travel if he drew up the load in a straight line as mentioned; and when elevating the load the horse is driven around the post and turned in direction of the starting point, and when the load has reached the proper point the rope is discharged or cast off from the post and the fork descends by its own gravity. When the load has been carried to the extreme point to which it is to be elevated, the horse is at the starting point, having travelled only the distance to raise the load, and not twice the distance, as he would have to travel in the ordinary modes of elevating the fork; that is, travelling in a direct line the distance necessary to elevate the load, and when it is discharged returning to the starting point.

Figure 1 is a perspective view of the invention.

Figure 2 is a sectional view of the casting-off pulley; and

Figure 3 is a plan thereof.

A is the post; B is the guide; C is the cap on the post; C' C' are stops therein; D is a stud on which the pulley E turns; E' E' are notches on the upper edge of the pulley E; F is the casting-off plate; F¹ is a stop on the under side to catch in the notches E' E'; F² is a projection on the under side of F to determine its motion between C' C'; G is the draught-rope; and H is the ground pulley.

The post A may be set in the earth or in any other substantial manner. On the side on which the horse advances is set the guide B, which may be set in the ground or attached to the post in such manner as that when the draught-rope strikes it, it will slide up until it falls into the groove on the pulley E. The post and guide may be of wood or metal. The cap C is of cast iron made to fit on the top of the post A, with the stud D cast thereon; and on this stud D plays the pulley E, which is also of cast iron, having a series of notches, E' E', on its upper edge, say about one inch apart, with the square shoulders of each in the direction of the horse as he faces the post in driving toward it. On the same stud D is the casting-off plate F, which is also of cast iron, and is made to turn horizontally over the pulley E. The outer end of F is curved downward below the lower side of the pulley E, and extends beyond the upper edge of the cap C, which outer end has also a skew on its upper surface sloping from the direction of the barn or ground pulley. On its under side is a stop, F¹, just over the notches E' E', which catches into them when the pulley is reversed, but which allows the notches to slide under it when the load is being elevated. On the side of the cap C are the stops C' C', which, with the projection F² on the under side of the cast-off plate, regulate the distance such plate may travel.

The mode of operation is as follows: The horse attached to the elevating rope in the usual way is driven toward the post A, and when he reaches it is turned around it; the rope then strikes the guide B and is carried by it up to the pulley E, as the horse advances. When the load has reached the desired point, the horse is stopped and the load dropped, and the horse being backed five or six inches allows the pulley E to turn backward, and the notches E' E' catching the stop F¹ carry back the said casting-off plate F, which from its form necessarily turns under the rope and consequently raises the rope up, and when it has turned back about one-third way round it has cast it off the pulley. If the load is carried to the highest point, the horse at the time the rope is cast off will have returned to the starting point, and all that is necessary is to turn him about, when he is ready to elevate another load.

The advantages of this invention are that it is cheap and simple, and allows of the moving of the horse in a smaller space and saves one-half of the travel. There are many other contrivances by which the rope may be cast off either by hand or automatically, which will readily occur to any one at once.

What I claim as my invention, and desire to secure by Letters Patent, is—

1. In a hay fork elevating apparatus or the like, the post A, in combination with the draught-rope G and ground pulley H.
2. The pulley E, and the casting-off plate F, constructed and operating in combination substantially as described.

JNO. H. CHAPMAN.
